ABSTRACT

A centrifugal pump which is provided with a structure for cooling and lubricating a sealing gland even when there is no pressure in the pump. The pump has a rotary shaft and an impeller fixed thereto for rotation therewith. A pump housing surrounds the impeller and rotary shaft. The housing has on one side of the impeller a suction inlet and on the other side thereof an inner surface which is directed toward the impeller. At this other side of the pump housing there is in the interior thereof a sealing gland which surrounds the shaft. At its inner surface which is directed toward the impeller the pump housing carries a deflecting structure for deflecting liquid from the impeller to the region of the sealing gland so that the latter will receive cooling and lubricating liquid even in a situation where pressure has not yet built up in the interior of the pump.

CENTRIFUGAL PUMP HAVING STRUCTURE FOR COOLING AND LUBRICATING A SEAL

BACKGROUND OF THE INVENTION

The present invention relates to centrifugal pumps. In particular, the present invention relates to a structure for improving the supply of liquid to a sealing gland in centrifugal pumps which may be either of the normal type or of the self-priming type.

In order to maintain the hollow interior of a centrifugal pump housing closed off from the outer atmosphere, particularly at the interior region of the housing which is under pressure, it is conventional to provide a sealing structure around the rotary shaft at the pressure side of the housing, although such sealing structure can also be provided at the suction side or at both sides of the pump housing. The life of this sealing structure depends upon the extent to which it is engaged by liquid which serves to lubricate the sealing structure and carry away the heat or friction which develops at the sealing structure.

At the interior of the pump where the sealing structure is located there is also, during operation of the pump, the liquid which is pumped thereby and which is in circular motion. Difficulties have been encountered during normal operation of pumps of the above type, with fairly great frequency, resulting from the fact that gases in the pumped liquid separate from the liquid and because of their specific weight circulate in the region of the pump shaft and in particular around the sealing gland or the like which is designed to seal off the interior of the pump housing from the exterior, so that a body of gas forms partially or entirely around the sealing structure.

When the sealing structure which surrounds the rotary shaft is thus situated partially or entirely in a body of gas, the sealing structure is no longer adequately cooled. As a result the temperature rises very sharply at the friction surface of the sealing gland, with the result that there is dry rotary movement of the sealing faces. The result is that there is a highly intense wearing of the sealing structure and eventual destruction thereof.

With normal centrifugal pumps which are not of the self-priming type, it has been proposed to prevent this undesirable result by providing liquid-circulating conduits at the exterior of the housing to assure a supply of cooling and lubricating liquid for the sealing gland, or the housing is formed in its interior with a bore extending from a chamber of relatively high pressure in the pump while utilizing the pressure drop for assuring a supply of sufficient liquid to the friction surfaces between the sealing gland and the shaft which it surrounds.

Particular difficulties have been encountered, however, in the case of self-priming pumps which during the initial priming phase of their operation suck a mixture of water and air into the pump so that there is an immediate formation, along the sealing gland, as described above, of a body of air and there is a dry running of the shaft in the sealing gland. During the priming period which may have a duration of several minutes the friction surfaces reach temperature on the order of several 100° C. When the pumping of the liquid such as water takes place subsequent to the priming phase of the operation, the body of gas around the sealing gland collapses and in a relatively short time the

friction surfaces are cooled down to the temperature of the pumped liquid.

However, when the sealing means which surrounds the shaft is made of a material such as a ceramic which is sensitive to thermal shock, there develops even during the initial priming phase of the operation cracks in the sealing structure due to the thermal stressing thereof. It is then possible for air to have access to the interior of the pump through such cracks or fissures which form due to the thermal stressing. The result is that such pumps require progressively longer priming periods, and in some cases the self-priming operation is completely prevented from taking place. Even in the case of normal centrifugal pumps which do not have self-priming it is possible for gas bodies to form around the sealing gland resulting in dry running and destruction of the sealing structure, as pointed out above.

Particularly in the case of a self-priming centrifugal pump, during the priming period there is no building of pressure in the interior of the pump, so that there is an insufficient pressure drop to assure adequate circulation in liquid-circulating conduits or bores which may be provided to direct cooling and lubricating liquid to the sealing structure. Such circulating conduits and bores connect the pressure chamber of the pump with the suction chamber thereof. In the case where a pump is mounted at its pressure side, this connection is made by relief bores formed in the impeller itself. As a result the periods of time required for priming become undesirably long.

Moreover, since the bores or conduits provided for circulation of cooling and lubricating liquid are closed except for the opposed ends thereof, such passages are easily plugged. In addition they are difficult to manufacture particularly in the case of materials which are difficult to work with such as ceramic, glass, or other highly ductile or hard materials. When mass production techniques are used, such as metal mold or die casting or plastic die casting, which normally do not require any subsequent machining operations, it is essential with structures of the above type which require circulating conduits or bores to provide additional working of the cast bodies.

Therefore, the provision of circulating conduits or bores, in addition to the extensive operations and accompanying high costs involved, require a pressure drop which is essential for their proper operation and which cannot always be established.

SUMMARY OF THE INVENTION

It is accordingly a primary object of the present invention to provide for centrifugal pumps of the above type a structure which will assure sufficient cooling and/or lubrication of the sealing glands with the liquid which is pumped under all operating conditions.

Thus, it is an object of the present invention to provide for a centrifugal pump a structure which will supply cooling and lubricating liquid to the sealing means even under conditions where no pressure has yet built up in the pump.

Yet another object of the present invention is to provide for a centrifugal pump a structure capable not only of assuring an adequate supply of cooling and lubricating liquid for the sealing glands but also capable of assuring that there will be no plugging or stoppage of the flow of cooling and lubricating liquid to the sealing gland structure.

Furthermore it is an object of the present invention to provide a centrifugal pump structure of the above general type which can be readily manufactured by mass production techniques such as by metal or plastic casting, without requiring subsequent machining operations or the like so that the cost of manufacture of the structure of the invention is greatly reduced as compared with conventional pump structures.

Thus, it is a general object of the present invention to provide for centrifugal pumps a structure which will assure for the sealing glands thereof a long operating life with an effective prevention of leakage of air into the pump through the sealing gland structure.

According to the present invention the centrifugal pump structure includes a rotary shaft having an impeller fixed thereto for rotation therewith. The shaft and impeller are surrounded by a pump housing which has on one side of the impeller a suction inlet and on the other side thereof an inner surface which is directed toward the impeller while being spaced therefrom. At the region of this latter inner surface of the pump housing a sealing means surrounds the rotary shaft. A deflecting means of the invention is carried by the pump housing at the latter inner surface thereof for deflecting liquid from the impeller to the sealing means even under conditions where there is no pressure in the housing.

BRIEF DESCRIPTION OF DRAWINGS

The invention is illustrated by way of example in the accompanying drawings which form part of this application and in which:

FIG. 1 is a sectional elevation of a pump according to the invention, the section of FIG. 1 being taken in a plane which contains the pump axis and FIG. 1 showing the structures situated above the latter axis;

FIG. 2 is a sectional elevation of another embodiment of a pump according to the invention, the section of FIG. 2 also being taken in a plane which contains the pump axis and FIG. 2 also showing only structure located above the latter axis, this structure which is shown in FIGS. 1 and 2 being a mirror image of the structure located below the axis; and

FIG. 3 is a schematic representation of various different forms which the structure of the invention may take.

DESCRIPTION OF PREFERRED EMBODIMENTS

Referring to FIG. 1, there is illustrated therein a pump housing 3 having a suction inlet 8. Within the pump housing is located a rotary impeller 4 which during operation of the pump directs liquid sucked in through the inlet 8 to the outer spiral pressure passage 9. By way of an unillustrated motor the impeller 4 is driven through a rotary shaft 10 which is driven from this motor and to which the impeller 4 is coaxially fixed.

A supporting ring 2 surrounds the shaft 10 and serves to mount the housing 3 thereon. A sealing means 1 in the form of a known sealing gland structure surrounds the shaft 10 for providing the required sealing of the interior of the housing 3 from the exterior, the sealing means 1 being urged toward the mounting ring 2 in any suitable way such as, for example, by the illustrated coil spring 11 which at an end distant from the sealing means 1 presses against a part of the impeller 4 and which engages the sealing means 1 to press the latter to the left, as viewed in FIG. 1, against the ring 2. In this

way the sealing means 1 is maintained in a fixed position fluid-tightly surrounding and engaging the shaft 10. The suction inlet 8 is situated at the suction side of the impeller 4 while the interior space of the housing 3 between the impeller 4 and the left wall of the housing 3, as viewed in FIG. 1, forms an inner pressure side of the housing 3. Thus, the left wall of the housing 3, as viewed in FIG. 1, has an inner surface directed toward and spaced from the impeller 4, and in accordance with the invention at this inner surface of the housing 3 a deflecting means 5a is provided for deflecting liquid from the impeller 4 to the region of the sealing means 1 for cooling and lubricating the latter even under operating conditions where no substantial pressure has yet built up in the interior of the pump housing. In the particular embodiment of the invention which is illustrated in FIG. 1 this deflecting means is in the form of an elongated groove formed in the inner surface of the housing 3 which is directed toward the impeller 4, and this groove communicates freely with the interior of the housing 3 and extends substantially radially with respect to the shaft 10 from the region of the sealing means 1 outwardly away from the shaft 10 by a distance at least as great as the outer periphery of the impeller 4 from the shaft 10. As is apparent from FIG. 1 the outer end of the groove 5a is situated from the shaft 10 by a distance somewhat greater than the distance of the outer periphery of the impeller 4 from the shaft 10. Thus, as soon as any liquid is thrown from the outer periphery of the impeller 4, even while there is still a substantial amount of gas in the interior of the pump, some of this liquid will reach the groove 5a, and at least one of the side surfaces of the latter will deflect the liquid inwardly to the sealing means 1 so as to provide cooling and lubrication thereof even if the operating conditions are such that no pressure has yet built up in the pump housing 3. Thus, one of the side surfaces of the groove 5a, which communicates over its entire area with the hollow interior of the pump housing 3, forms a deflecting means for deflecting part of the liquid to the sealing means 1, and it will be noted that the side surfaces of the groove 5a extend at an angle with respect to the inner surface of the housing 3 which is directed toward the impeller 4.

The embodiment of the invention which is illustrated in FIG. 2 shows that type of pump where the housing 3 has an inner annular projection 7 surrounding a projection of the impeller 4 and participating in the support of the impeller 4 for rotation by way of a split ring 6. With this type of pump the groove 5b, which otherwise conforms in all respects with the groove 5a, extends completely through the annular projection 7.

Thus, with the above embodiments of the invention by way of the grooves 5a and 5b the friction surface of the sealing means 1 is supplied with the pumped liquid even when there is an insufficient pressure drop in the pump, as is the case particularly with self-priming centrifugal pumps. The grooves 5a, 5b are arranged in such a way that they deflect part of the circulating liquid in the pump and direct the deflected part of the stream to the friction surfaces of the sealing means. For this purpose it is only necessary for the groove to extend through a relatively short radial distance. It is sufficient if the grooves 5a or 5b extend along a straight line from an inner end where the sealing ring 1 is located outwardly along a vertical or inclined line.

It is not essential that the deflecting means be formed by grooves such as the grooves 5a and 5b which extend radially with respect to the common axis of the shaft 10 and the impeller 4. Thus, FIG. 3 illustrates examples of further different embodiments of the present invention. FIG. 3 schematically illustrates the pump housing 3 and shows the spiral pressure outlet 9 along which the liquid flows in the direction of the arrows 20. FIG. 3 also illustrates a circle 21 surrounding the common axis of the shaft 10 and the impeller 4, the impeller 4 itself being indicated in phantom lines in FIG. 3. Thus, it will be seen from FIG. 3 that it is possible to provide a deflecting means of the invention such as the deflecting means 5c which extends radially with respect to the common axis of the shaft 10 and the impeller 4, but in this case the deflecting means 5c takes the form of a plurality of projections extending from the inner surface of the housing 3 toward the impeller with these projections being distributed along opposite sides of a line which extends radially from the common axis of the shaft 10 and the impeller 4. These projections can take any form such as bosses of circular cross section or rectangular projections as illustrated in FIG. 3.

Moreover, it is not essential that the deflecting means extend radially. For example there is shown in FIG. 3 a deflecting means 5d in the form of a pair of ribs fixed to and projecting from the inner surface of the housing 3 toward the impeller 4. These ribs are situated on opposite sides of a line which extends tangentially with respect to the circle 21. Thus, it is apparent that instead of forming a groove on the inner surface of the housing 3 it is also possible to provide the housing 3 at its inner surface which is directed toward the impeller 4 with raised projections having an arrangement such as those shown for the deflecting means 5c and 5d for the purpose of assuring an adequate supply of cooling and lubricating liquid to the sealing means.

Also, it is possible to provide a deflecting means 5e in the form of a single elongated projection extending from the inner surface of the housing 3 toward the impeller 4, and having a curved configuration as illustrated in FIG. 3. It will be noted that the curvature of the deflecting means 5e is in the same general direction as the direction of flow of the liquid indicated by the arrows 20. Thus, the deflecting means 5e takes the form of a deflecting vane which also operates very effectively to assure an adequate supply of cooling and lubricating liquid to the sealing means. This vane 5e may extend along an arc of a circle or may have a spiral configuration. Thus part of the liquid in the pump housing will always be deflected by the deflecting means 5e to the sealing means. Also the deflecting means may take the form of a single rib or vane 5f extending radially with respect to the shaft 10, as shown in FIG. 3.

It is apparent, therefore, that instead of providing grooves as shown in FIG. 2 it is also possible in accordance with the invention to provide deflecting means in the form of ribs, vanes, projections of any shape, or the like, with the deflecting means extending radially or tangentially or along a curved path. With all of these configurations the deflecting means 5a-5f are always arranged in such a way that they will assure the adequate supply of cooling and lubricating liquid to the sealing means.

Moreover, it will be noted that in all of the above-described embodiments of the invention it is possible to mold by any known molding technique or even to press

the deflecting means of the invention into the material of the housing 3, so that the deflecting means is always formed integrally therewith in such a way that expensive operations subsequent to the molding operations or the like can be eliminated.

Thus, because of these possibilities of mass production of the pump housing when providing it with the deflecting means of the invention it is possible to make the housing and the impeller itself of any rigid material such as a metal and/or plastic.

Thus, with the structure of the invention there is the advantage of assuring cooling and lubricating of the sealing means independently of the presence of a pressure drop, and of course with the structure of the invention the priming durations for self-priming pumps will not become progressively longer and there is no danger of stopping up or plugging of the path of flow of the cooling and lubricating liquid to the sealing means.

What is claimed is:

1. In a centrifugal pump, a rotary drive shaft, an impeller carried thereby for rotation therewith, said impeller having an outer periphery situated at a given distance radially from said shaft, a pump housing surrounding said drive shaft and impeller, said housing having on one side of said impeller a suction inlet and on the other side of said impeller an inner surface spaced from and directed toward said impeller, sealing means surrounding said shaft and situated in said housing at the region of said inner surface thereof, and deflecting means carried by said housing at said inner surface thereof and coacting with said impeller for deflecting liquid from said impeller to said sealing means for cooling and lubricating said sealing means even if there is no pressure in said housing, said deflecting means including at least one deflecting surface which communicates freely over its entire area with the interior of said housing and which extends angularly with respect to said inner surface of said housing, said deflecting surface having an inner end situated in the region of said sealing means and extending from said inner end outwardly away from said shaft and terminating in an outer end spaced from said shaft by a distance greater than said given distance, so that said deflecting means extends away from said shaft to an extent greater than the outer periphery of said impeller to receive liquid thrown from said impeller at the outer periphery thereof even when there still is no liquid in the space between said inner surface of said housing and said impeller.
2. The combination of claim 1 and wherein said deflecting means is in the form of a groove formed in said inner surface and having opposed side surfaces one of which forms said deflecting surface.
3. The combination of claim 1 and wherein said deflecting means projects from said inner surface toward said impeller.
4. The combination of claim 1 and wherein said deflecting means extends radially with respect to a common axis of said shaft and impeller.
5. The combination of claim 1 and wherein said deflecting means extends tangentially with respect to a circle which concentrically surrounds a common axis of said shaft and impeller.
6. The combination of claim 1 and wherein said impeller directs liquid in a predetermined direction around a common axis of said shaft and impeller, said deflecting means being in the form of a curved deflect-

ing vane projecting from said inner surface toward said impeller and being curved in the same general direction as the flow of liquid around said axis.

7. The combination of claim 1 and wherein said deflecting means includes a plurality of projections projecting from said inner surface towards said impeller and distributed on opposite sides of a line which extends from the region of the outer periphery of said impeller to the region of said sealing means.

8. The combination of claim 1 and wherein said housing has an annular projection extending from said inner surface thereof to the region of said impeller and coact-

ing therewith to participate in supporting the latter for rotation, and said deflecting means extending through said annular projection.

9. The combination of claim 1 and wherein said impeller and housing made of substantially rigid materials such as metal and/or plastic.

10. The combination of claim 3 and wherein said deflecting means is in the form of a single rib extending radially with respect to the common axis of said shaft and impeller.
